Patented Jan. 5, 1915.

UNITED STATES PATENT OFFICE.

IRA J. BRADSHAW, OF WAUKEGAN, ILLINOIS, ASSIGNOR OF ONE-FOURTH TO JOHN S. WHYTE, ONE-FOURTH TO PHILIP C. REGAN, AND ONE-FOURTH TO DAVID ADAMS, ALL OF WAUKEGAN, ILLINOIS.

RAIL-ANCHOR.

1,124,206.

Specification of Letters Patent.

Patented Jan. 5, 1915.

Application filed February 28, 1914. Serial No. 821,629.

To all whom it may concern:

Be it known that I, IRA J. BRADSHAW, a citizen of the United States, residing at Waukegan, in the county of Lake and State of Illinois, have invented certain new and useful Improvements in Rail-Anchors, of which the following is a specification.

This invention relates to rail anchors, sometimes known as rail anti-creepers, and is designed and adapted to prevent the longitudinal creeping of railroad rails and the like.

One of the principal objects of my invention is the provision of a rail anchor which will tightly clamp the rail base and by bearing against the tie prevent creeping of the rail and which will at the same time permit contraction of the rail without any consequent loosening of the anchor and without any reduction of its efficiency, or other ill effects.

A further object of the invention is to provide a device of the character described which may be positioned without auxiliary fastenings to the rail or to the tie and which will form a more tenacious engagement between the tie and rail as the tendency to creep and the forces creating a tendency to creep increase.

A still further object is the provision of a rail anchor of simple and cheap construction which may be easily applied and which will consist of few parts.

Other objects and advantages of the invention will be apparent as it is better understood from the following description when considered in connection with the accompanying drawing, illustrating a preferred embodiment thereof.

On the drawing, Figure 1 is a plan view showing a rail anchor embodying my invention operatively positioned; Fig. 2 is an end view of the anchor; Fig. 3 is a plan view of the same, and Fig. 4 is a section taken substantially on the line 4—4 of Fig. 3.

For the purpose of illustrating my invention I have shown it embodied in a rail anchor generally designated at 5 in Fig. 1 and operatively engaged with the base

flanges 6 of a rail 7. The anchor embraces 50 these flanges and bears against an ordinary wooden railway tie 8.

The anchor shown on the drawing comprises essentially a clamping member 9 which engages the rail, as will be later described, a sleeve 11 secured to the clamping member by an offset portion 10 integral with both the sleeve and clamping member, a plunger 13 arranged in said sleeve and a spring 12 positioned in the sleeve and bearing against the plunger. The plunger constitutes an abutment for the anchor and when the device is operatively positioned bears against the tie and prevents creeping of the rail, as will be later understood. The 65 clamping member is provided with a transversely extending slot 15, which is undercut on each side at 16 to engage the flanges of the rail. The distance between the sides 15' of the slot 15 is somewhat less than the 70 width of the base of the rail and the distance between the inner surfaces 17 of the undercut portions is somewhat greater than this width. These dimensions are such as to permit the clamping member to be positioned by engaging one base flange of the 75 rail in one of the undercut portions 16 and then lifting the other side of the clamping member until the wall 15' has passed above the flange at this side and this flange is disposed in the other undercut portion. The flanges are held in the undercut portions when the clamping member is in its normal operative position, as seen in Fig. 1. When in this position the clamping member is disposed across beneath the rail at an angle with the forward end of the inner face 17 of the undercut portion 16 remote from the sleeve 11 and the rear end of the inner face 17 of the undercut portion 16 adjacent said 80 sleeve in firm engagement with the adjacent surfaces of the base flanges. The engagement between these surfaces is indicated at 85 17' in Fig. 1 and in order that an appreciable portion of the faces 17 may engage the 90 rail these faces are slightly rounded as at 18 in Fig. 3. The inner faces 17 and preferably the adjacent surfaces of the rail are

scarred or roughened to prevent any slipping of the rail in the clamping member.

The offset portion 10 is relatively thin and is reinforced by ribs or webs 21 suitably arranged. The sleeve 11 is, as has already been stated, hollow and is closed at one end with an integral end wall 22 offset at 23 to provide a recess in which may be secured an end of a plunger rod 24 which secures the plunger 13 in place. The other end of the sleeve is open and the plunger 13 is loosely and telescopically engaged therein. The plunger is preferably also hollow and consists in the present instance of a head 25 having a centrally disposed outwardly extending projection 26, which is adapted to engage the tie, and an inwardly extending sleeve 27 forming the hollow portion of the plunger. The stem or rod 24 extends from the head 25 to the outer face of the inset portion 23 of the rear wall of the sleeve 11, where it is upset at its end at 28. The spring 12 bears against the rear wall 22 of the sleeve and against the head 25 of the plunger and preferably encircles the stem or rod 24 of the plunger and the inset portion 23 of the rear wall of the sleeve.

The device is positioned by engaging the base of the rail with the clamping portion 30 of the anchor and moving it down until the projection 26 of the plunger engages the side of the tie and then driving both sides of the clamping portion toward the tie as far as possible or until the head of the plunger bears against the end of the sleeve and the spring is under compression and the clamping member is arranged as already described. The side of the clamping member remote from the plunger is always maintained as far in advance of the side adjacent the plunger as possible in order that a strong binding engagement between the rail base and the inner walls of the undercut portions 16 may be maintained.

45 The anchor is arranged so that the creeping tendency will be toward the tie and the plunger may be at the inside or at the outside of the track. The rail in creeping must carry the end of the clamping member 50 nearer the tie which is impossible by reason of the engagement of the flanges of the rail with the inner walls of the undercut portions 16, the least movement of the rail toward the tie binding it more tightly in the 55 undercut clamping portion. Contraction of the rail will not release the rail or reduce the tenacity of the engagement between the rail and anchor in any respect as the spring 12 maintains the relationship as the body 60 portion of the anchor is carried away from the tie by contraction of the rail, and returns the parts to the normal uncontracted relation upon subsequent expansion of the

9 rail. The plunger preferably fits loosely in the sleeve 11 so that the clamping member 61 9 may vibrate with the rail when a train of 71 heavily loaded cars passes thereover without disturbing the position of the plunger or moving the projection 26 from its firm and stationary engagement with the tie. 76

The device is simple and may be cheaply constructed and can be easily and quickly positioned.

It will be apparent that various changes 71 may be made in the form and construction of the parts and their arrangement without departing from the spirit and scope of the invention or sacrificing any of its material advantages, the form hereinbefore described being merely a preferred embodiment 81 thereof.

I claim:

1. A rail anchor comprising a member adapted to engage the base of a rail and carrying a yielding abutment adapted to engage the side of a tie.

2. A rail anchor comprising a member adapted to engage the base of a rail and provided with an offset yielding member adapted to engage the side of a tie.

3. A rail anchor comprising a member adapted to engage the base of a rail and having an offset portion, and a member telescoping with said offset portion and adapted to engage the side of a tie.

4. A rail anchor comprising a member adapted to engage the base of a rail and provided with an offset portion, a member telescoping with said offset portion and adapted to engage the side of a tie, and yielding means interposed between said offset portion and the member telescoping therewith.

5. A rail anchor comprising a member adapted to engage the base of a rail and provided with an offset integral sleeve, a plunger mounted in said sleeve and adapted to engage the side of a tie, and a spring interposed within said sleeve and coacting therewith and with the plunger to permit contraction of the rail.

6. A rail anchor comprising a member having a slot in which the base of a rail is adapted to rest and provided with an offset portion, the width of the slot in said member being greater than the width of the base of the rail, and means coacting with a tie and with said offset portion for causing the rail to bind in the slot to prevent creeping, said means being yielding to permit contraction of the rail without loosening the anchor.

7. A rail anchor comprising a member adapted to engage the side of a rail and provided with a hollow sleeve, a hollow plunger arranged in said sleeve and adapted to

engage the side of a tie, and a spring arranged in said sleeve and in said plunger.

8. A rail anchor comprising a clamping member adapted to engage the base of a rail, and an abutment adapted to engage the side of a tie, said abutment being loosely secured to said clamping member to permit

the clamping member to vibrate with the rail without disturbing the position of the abutment.

IRA J. BRADSHAW.
